(57) **CLAIM**

The design for a vacuum cleaner, as shown and described.

DESCRIPTION

FIG. 1 is a side perspective view of the vacuum cleaner.

FIG. 2 is a bottom perspective view of the vacuum cleaner.

FIG. 3 is a front elevational view of the vacuum cleaner.

FIG. 4 is a back elevational view of the vacuum cleaner.

FIG. 5 is a right-side elevational view of the vacuum cleaner.

FIG. 6 is a left-side elevational view of the vacuum cleaner.

FIG. 7 is a top plan view of the vacuum cleaner.

FIG. 8 is a bottom plan view of the vacuum cleaner.

FIG. 9 is a side perspective view of the vacuum cleaner in an exploded state, absent of the vacuum foot.

FIG. 10 is a side perspective view of the vacuum cleaner in an assembled state.

FIG. 11 is a side perspective view of the vacuum cleaner in a second assembled state.

FIG. 12 is a side perspective view of the vacuum cleaner in a third assembled state.

FIG. 13 is a bottom perspective view of the vacuum cleaner of FIG. 12.

FIG. 14 is a front elevational view of the vacuum cleaner of FIG. 12.

FIG. 15 is a rear view of the vacuum cleaner of FIG. 12.

FIG. 16 is a right-side view of the vacuum cleaner of FIG. 12.

FIG. 17 is a left-side view of the vacuum cleaner of FIG. 12.

FIG. 18 is a top plan view of the vacuum cleaner of FIG. 12; and,

FIG. 19 is a bottom plan view of the vacuum cleaner of FIG. 12.

1 Claim, 19 Drawing Sheets
